Patented Aug. 22, 1922.

O.C. Snell Inventor
By *Jack K. Keeley*
Attorney

UNITED STATES PATENT OFFICE.

OWENS C. SNELL, OF DALLAS, TEXAS.

SOCKET WRENCH.

1,426,682.

Specification of Letters Patent. Patented Aug. 22, 1922.

Application filed October 10, 1921. Serial No. 506,777.

To all whom it may concern:

Be it known that I, OWENS C. SNELL, a citizen of the United States, residing at Dallas, in the county of Dallas and State 5 of Texas, have invented certain new and useful Improvements in Socket Wrenches, of which the following is a specification.

This invention relates to new and useful improvements in socket wrenches.

10 The object of the invention is to provide a socket wrench of that type which includes an extension for holding the nut against rotation, while the bolt is being rotated to disconnect the same, or vice versa. The invention 15 has particularly to do with that type of wrench which is adapted to travel a pair of flanges such as those forming part of an engine base and hold the nut against rotation while the bolt is being unscrewed.

20 A particular object of the invention is to provide a keeper for engaging the upper end of a castle nut such as are employed where cotter pins are used. Another feature of the invention resides in means for expelling 25 the bolt from the socket after said bolt has been unscrewed.

A construction designed to carry out the invention will be hereinafter described together with other features of the invention.

30 The invention will be more readily understood from a reading of the following specification and by reference to the accompanying drawings, in which an example of the invention is shown and wherein:

35 Fig. 1 is an elevation of a wrench constructed in accordance with my invention,

Fig. 2 is an enlarged vertical sectional view of the upper end of the wrench,

Fig. 3 is an enlarged cross section on the 40 line 3—3 of Fig. 1,

Fig. 4 is a detail showing the underside of the keeper, and

Fig. 5 is a plan view of the socket.

In the drawings the numeral 10 designates 45 a shank which may be separately or integrally connected with a crank 11 such as is employed with an ordinary boring brace. A hand rest 12 is suitably mounted to rotate on the lower end of the crank. The details 50 of this construction are immaterial.

At its upper end the shank is fastened in the lower end of a socket sleeve 13, which preferably has angular internal walls so as to receive the head A, of a bolt B. Within 55 the socket sleeve I mount a plunger 14 which is provided with a longitudinal retaining

groove 15 receiving a set screw 16 mounted in the side wall. The set screw permits the plunger to move vertically in the socket and to be depressed by the head A, but limits the movement of said plunger. The plunger rests upon a coiled spring 17 within the sleeve, which spring tends to force the plunger upwardly to either expel the head A of the bolt therefrom or to force the socket 65 sleeve away from the said head A when the wrench is removed from the work.

A short bar 18 is slideable on the shank 10. A keeper plate 19 is also mounted on the shank immediately below the sleeve 13 and 70 is supported by the upper end of a coiled spring 20 which encircles the shank and rests upon the bar 18. An extension 21 is mounted in apertures in the plate 19 and the bar 18, being fastened in the latter by a 75 thumb screw 22. The extension 21 has a lateral offset 23 which carries an inwardly directed head 24 overhanging the socket sleeve and the plate 19. The construction of this head is important. The head is reduced 80 and provided with a round opening 25 and a shoulder 26. Below the opening 25, the head has an angular socket 27.

In using the wrench the head is displaced from the socket 13, which causes the bar 18 85 to be moved upwardly on the shank so that the spring 20 is placed under tension. This permits a projection as C, to be received between the head and the socket with the head A of the bolt depending into the socket 90 sleeve which is pressed up against the underside of the projection C, whereby the plunger 14 is depressed. The head is engaged over the nut D so that the upper portion of the castle nut is received within said opening 95 and the lower angular portion is received in the socket 27. By this arrangement the head cannot be displaced laterally from the nut and the latter is held against rotation. By revolving the crank 11 the bolt B is rotated and unscrewed from the nut D. The spring 17 is constantly under tension, and this tends to raise said plunger or depress 100 said socket sleeve whereby the head A is partially expelled from the upper end of the sleeve 13 and is prevented from wedging or sticking in said socket during the operation. It will be seen that by adjusting the extension 21, projections of varying widths may be engaged between the head and the 105 socket.

A wrench of this character is of particu-

lar value because it will not slip off the work and will operate quickly. No time will be lost in extracting the head A of the bolt from the socket and the device is substantial and easy to operate.

The round opening 25 is of great importance, as where the nut D is unscrewed from a long bolt, the head would easily be displaced from the nut. The guard or retainer formed by the rim of the opening holds the head on the nut and fits readily over the rounded castle nut or bolt, yet permits the angular socket 27 to readily engage the nut.

Various changes in the construction and dimensions as well as modifications, may be made without departing from the spirit of the invention.

What I claim, is:

1. In a socket wrench, a revoluble shank, a socket fixed on the end of the shank, a bar slidable on the shank, a keeper mounted on the shank between the bar and the socket, a coiled spring surrounding the shank be-

tween the bar and the keeper, an extension 25 slidable through the keeper and adjustably fastened in the bar, and a head on the end of the extension overhanging the socket and provided with a round opening for receiving a nut and an angular socket below the opening for engaging the lower portion of a nut.

2. In a socket wrench, a revoluble shank, a socket fixed on the end of the shank, a bar slidable on the shank, a keeper mounted on the shank between the bar and the socket, 35 a coiled spring surrounding the shank between the bar and the keeper, an extension slidable through the keeper and adjustably fastened in the bar, a head on the end of the extension overhanging the socket and 40 provided with a round opening for receiving a nut and an angular socket below the opening for engaging the lower portion of a nut, and a spring plunger in the socket of the shank for engaging a bolt head received 45 in said socket.

In testimony whereof I affix my signature.
OWENS C. SNELL.
